US0D1095673S

(12) **United States Design Patent** (10) **Patent No.:** **US D1,095,673 S**
(45) **Date of Patent:** **** Sep. 30, 2025**

(54) **FOLDER FILER**

- (71) Applicant: **ACCO Brands Corporation**, Lake Zurich, IL (US)
- (72) Inventors: **Jeffrey M. Akins**, Springboro, OH (US); **Jeremy L. Mudd**, Bellbrook, OH (US); **Andrew J. Miller**, Phoenixville, PA (US); **Noah E. Dingler**, Phoenixville, PA (US); **Kevin Y. Shin**, San Diego, CA (US); **Patrick Nolan**, Royersford, PA (US)
- (73) Assignee: **ACCO Brands Corporation**, Lake Zurich, IL (US)

(**) Term: **15 Years**

(21) Appl. No.: **29/904,283**

(22) Filed: **Oct. 3, 2023**

CLAIM

The ornamental design for a folder filer, as shown and described.

DESCRIPTION

FIG. 1 is a top perspective view of the folder filer according to our new design, shown with a top flap in a secured configuration;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top perspective view of the folder filer of FIG. 1 shown with the top flap in a tucked configuration.

The broken lines in the drawings illustrate portions of the folder filer that form no part of the claim.

1 Claim, 6 Drawing Sheets
